DESIGN FOR A SET OF PLAYING CARDS

John Acosso and Carmine De Donato, Brooklyn,
N. Y.

Application October 19, 1933, Serial No. 49,516

Term of patent 14 years

To all whom it may concern:

Be it known that we, JOHN ACOSO and CARMINE DE DONATO, both citizens of the United States, both residing at Brooklyn, in the county of Kings and State of New York have invented a new, original, and ornamental Design for a Set of Playing Cards, of which the following is a specification, reference being had to the accompanying drawing, forming a part thereof.

The figure is a face view of a set of playing cards, showing our new design.

The dominant feature of the cards is a square frame within a rectangular outside of the cards,

representations of baseball players and the implements for playing the game within said square frame, and card values on the cards outside of the square frame. The set of playing cards consists of 16 cards as shown.

We claim:

The ornamental design for a set of playing cards, as shown and described.

In testimony whereof we have affixed our signatures.

JOHN ACOSO.
CARMINE DE DONATO.
